tion of Delaware

Filed Aug. 3, 1966, Ser. No. 3,323

Term of patent 14 years

(Cl. D26—1)

FIG. 1

FIG. 2

FIG. 1 of the drawing is a front perspective view of a cabinet for electrical apparatus in accordance with the present invention.

FIG. 2 is a rear perspective view thereof.

The dominant features of the design reside in the full line portions thereof, which full line portions are characterized by the band-like area between the face of the cabinet and the body of the cabinet rearwardly of said band-like area.

I claim:

The ornamental design for a cabinet for electrical apparatus, substantially as shown and described.
